UNITED STATES PATENT OFFICE

JOHN HELENBERG, OF HOUSTON, TEXAS

STEAM VALVE GEAR

Application filed August 30, 1926. Serial No. 132,527.

The present invention relates to a steam valve gear and has for its prime object to provide an improvement over the steam gear that is used on the Worthington feed water 5 heater and pump and over any other steam actuated valve gear known in the art.

Another important purpose and object of the invention is to reduce the first cost and the cost of the annual maintenance and furthermore to increase the reliability and simplicity by eliminating all unnecessary plungers, cylinders, slide valves, and ports.

With the above and numerous other objects in view as will appear as the description 15 proceeds, the invention resides in certain novel features of construction, and in the combination and arrangement of parts as will be hereinafter more fully described and claimed.

20 In the drawings:

Figures 1, 2 and 3 are sectional views showing the parts of the device in different positions,

Figure 4 is an elevation of the casing for 25 the slide valve,

Referring to the drawings in detail, it will be seen that the letter C represents a cylinder with a piston P mounted for reciprocation therein. This cylinder is provided with 30 ports 1, 2, 3, 4, 5 and 6, ports 1, 3 and 5 being grouped at the top of the cylinder and ports 2, 4 and 6 being grouped at the bottom of the cylinder. Conduits, 1^a, 2^a, 3^a, 4^a, 5^a and 6^a lead respectively from ports 1, 2, 3, 4, 5 and 35 6. The conduits 3^a and 4^a are branches of conduits 5^a and 6^a respectively. Conduits 1^a, 2^a, 5^a and 6^a lead to ports provided in a valve casing 8. The ports of the casing are shown to advantage in Fig. 4 and include ports 9^b 40 and 10^b from which lead conduits 9 and 10 respectively to exhausts E and E'. The casing 8 is further provided with ports 5^b and 6^b communicating with conduits 5^a and 6^a respectively. The casing has ports 11^b and 12^b 45 communicating with conduits 11 and 12 respectively leading to exhausts E and E' respectively. The casing 8 is provided with ports 1^b and 2^b communicating with conduits 1^a and 2^a respectively. At the center the casing 8 is provided with the ports 7^b from which lead conduits 7 to the intake I. A valve V is 50 slidably mounted in the cylindrical casing 8 and includes an elongated body having an enlargement 14 at its center and enlargements 15 and 16 at its respective ends. Headed bolts 19 and 20 are threadedly engaged in the ends of the body of the valve V and have slidably mounted thereon auxiliary valves 17 and 18 respectively which are provided with openings 17' and 18'. The chamber between enlargement 14 and enlargement 15 in the casing 8 is denoted by the numeral 25 while the chamber between the enlargement 14 and the enlargement 16 is denoted by the numeral 26. The chamber in 55 which the auxiliary valve 17 operates is denoted by the numeral 27 and the chamber in which the other auxiliary valve 18 operates is denoted by the numeral 28.

From the above detailed description of the parts a clear understanding may be had of the operation of the device. The main positions of the valve V and the auxiliary valves 17 and 18 have been illustrated in Figs. 1, 2 and 3. Supposing the parts to be located as

shown in Fig. 1, and the piston P moving from top to bottom it will be seen that the steam from the intake I passes through the conduit 7, ports 7^b, chamber 25, conduit 1^a and port 1 to the top of the cylinder thereby 60 forcing the piston downwardly. The steam is further being exhausted through port 2, conduit 2^a, port 2^b, chamber 26, conduit 12, to exhaust E'. When the piston approaches the bottom end of the cylinder C it will 65 successively close ports 6 and 4 but when it reaches the bottom of the cylinder port 6 will be opened as is clearly illustrated in Fig. 2 whereby the live steam coming from the port 1 will pass through the port 6, conduit 6^a into chamber 28 and will build up a pressure 70 therein so as to cause the valve V to move upwardly to the position shown in Fig. 2 which will cause the closing of exhaust port 12^b and will close all communication of port 7^b with chamber 25 and communicate port 7^b with chamber 26. The enlargement 15 passes 75 by the port 11^b and communicates it with the chamber 25. It will therefore be seen that the live steam from the intake I will pass 80

100

through the conduit 7, port 7^b, chamber 26, conduit 2^a, and port 2 to the bottom of the cylinder C thereby moving the piston P upwardly and the exhaust steam will pass through port 1, conduit 1^a, port 1^b, chamber 25, port 11^b, conduit 11 to the exhaust E. As the piston moves upwardly it will reach the position shown in Fig. 3 so that a portion of the live steam will pass through branch 4^a, 10 conduit 6^a and expand in chamber 28 so as to move the valve V still further upwardly to the position shown in Fig. 3, thereby causing the enlargement 15 to engage the auxiliary valve 17 and move it upwardly to close port 9^b the same as auxiliary valve 18 closes port 10^b in Fig. 1.

I have described one cycle of operation which will clearly demonstrate the movement of the parts, particular attention being 20 called to the fact that the auxiliary valves are shifted by the heads of the bolts 19 and 20 and the enlarged portions 15 and 16. Thus the auxiliary valve 18 is shifted from the position shown in Fig. 2 to that shown 25 in Fig. 3 by the bolt 20. This steam valve gear is of the enclosed type and is entirely steam actuated. The entire mechanism consists of three moving parts which cause the movement of the piston P, namely a main 30 steam valve V and the two control or auxiliary valves 17 and 18 which control the admission and exhaust of steam to the ends of the main steam valve. The main steam valve V and the two control valves 17 and 35 18 are of the piston type and all are the same in size and function in the same control unit casing or bushing 8.

It is thought that the construction, operation, and advantages of this improved structure will now be understood by those skilled 40 in this art without a more detailed description thereof. The present embodiment of the invention has been disclosed in detail merely by way of example, since in actual 45 practice it attains the features of advantage enumerated as desirable in the statement of the invention and the above description. It will be apparent that changes in the details of construction, and in the combination and 50 arrangement of parts may be resorted to without departing from the spirit or scope of the invention as hereinafter claimed or sacrificing any of its advantages.

Having thus described my invention, what 55 I claim as new is:

In combination, a cylinder, a piston in the cylinder, said cylinder having a port at each end, a bushing casing having a pair of longitudinally spaced ports at each end, a 60 port at the center thereof and a pair of ports between the center port and each pair of end ports, a slide valve in the bushing casing having a central enlargement associated with the central port, enlargements at the ends of 65 the valve for association with the third men-

tioned ports, control valves for association with the end ports, a pair of headed pins on which the control valves are slid able, said pins engaging the first mentioned valve at the ends thereof, said control valves having 70 openings extending therethrough, conduits leading from the end ports of the cylinder to the inner ports of the pairs of ports, the central port of the casing having a conduit leading thereto from an intake means and the outer ones of the end ports being exhaust ports and the outer one of the intermediate ports in the casing between the end ports and the central ports being also exhaust ports.

In testimony whereof I affix my signature.
JOHN HELENBERG.
